(57) **CLAIM**

The ornamental design for a display panel with a computer-generated icon as shown and described.

DESCRIPTION

The file of this patent contains at least one drawing executed in color. Copies of this patent with color drawings will be provided by the Office upon request and payment of the necessary fee.

FIG. 1 is a front view of a display panel or portion thereof with a computer-generated icon according to the claimed design;

FIG. 2 is a top-right front perspective view of a display panel of an electronic device with the computer-generated icon according to the claimed design, where the electronic device is a notebook computer; and,

FIG. 3 is a front view of the display panel of the notebook computer with the computer-generated icon according to the claimed design.

The broken lines in FIG. 1 are included to depict portions of the display panel and form no part of the claimed design. The broken lines in FIGS. 2-3 are included to depict portions of the display panel and an example of the environmental structure of the electronic device, and form no part of the claimed design.
